(57) **CLAIM**

The ornamental design for an apparatus for breath analysis, as shown and described.

DESCRIPTION

FIG. 1 is a perspective view of a first embodiment of an apparatus for breath analysis showing our new design; FIG. 2 is a right side elevational view of the apparatus for breath analysis of FIG. 1;

FIG. 3 is a left side elevational view of the apparatus for breath analysis of FIG. 1;

FIG. 4 is a rear elevational view of the apparatus for breath analysis of FIG. 1;

FIG. 5 is a front elevational view of the apparatus for breath analysis of FIG. 1;

FIG. 6 is a top plan view of the apparatus for breath analysis of FIG. 1; and,

FIG. 7 is a bottom plan view of the apparatus for breath analysis of FIG. 1.

The broken lines shown in the drawings illustrate portions of the apparatus for breath analysis that form no part of the claimed design.
